ABSTRACT OF THE DISCLOSURE

A synthetic detergent toilet bar which consists essentially of (a) a mixture of an alkene sulfonate and a hydroxy alkane sulphonate, said hydroxyalkane sulphonate being a mixture of alkene-3-hydroxy-1-sulphonate, alkane-4-hydroxy sulphonate, and alkane-2-hydroxy-1-sulphonate, and having no more than 2% by weight of the alkane-2-hydroxy-1-sulphonate, and (b) a fatty alcohol sulfate.

The invention relates to an improved toilet bar in which the active consists of synthetic detergents.

Bars made entirely from synthetic detergents are usually deficient in plasticity. It has previously been proposed to add a plasticizing amount of water (water has long been known to have a plasticizing effect in any such system) but although this solution to the problem enables the bar to be manufactured on ordinary soap-processing equipment, when the water content is reduced on storage by natural evaporation the bar may crack or become excessively hard so that an undue amount of rubbing is necessary to get a lather when the tablet is taken into use.

Another solution which has been proposed is to combine the unduly hard detergent with one or other of the unduly soft detergents which could not, by themselves, be used to manufacture an acceptable tablet. These soft detergents, however, are often among those least mild to the skin and confer their irritancy to the combination bar in due proportion to the amount added to the combination bar, which amount must, on this account, be strictly limited. It is also known that some hard detergents are unduly irritant, sodium dodecyl sulphate being particularly well known in this respect.

Accordingly, this invention provides a toilet bar consisting essentially of synthetic detergents, wherein the synthetic detergents consist of an alkali metal or alkaline earth metal salt of an alkene sulphonate as herein defined in conjunction with a different non-soap detergent. By "alkali metal" is meant lithium, sodium, potassium and ammonium and by "alkaline earth metal" is meant calcium and magnesium.

Such tablets are mild to the skin and possess the desirable attributes of good lathering in hot or cold, hard or soft water in conjunction with a reasonable rate of wear.

Toilet bars which consist essentially of alkane sulphonates and alkene sulphonates are the subject of our copending British patent application No. 8,532/66. Such bars are not within the scope of the present application.

The alkene sulphonates for use in this invention may be obtained by the well-known series of reactions from

2

the actions of SO_3 or similar sulphonating agents on alpha-olefins. The alkene sulphonates preferred are those which result from reactions of alpha olefins having C_{11-24} chain lengths, with a "strong" sulphonating agent, particularly sulphur trioxide in an inert gas such as air, and wherein the liquid olefin and the SO_3 /air streams are contacted in a reactor designed to ensure a short time of contact i.e. less than 10 minutes, preferably less than 1 minute, and provided with a means for removing the heat of re-hydrolysis followed by neutralisation, or by alkaline hydrolysis yields salts of sulphonic acids. These sulphonic acids are complex mixtures of alkane hydroxy sulphonic acids and alkene acids, with a proportion of sulphonic acids of low equivalent weight which are conveniently termed "di-sulphonic acids," without implying that they are wholly true disulphonic acids. They may contain in addition to true disulphonic acids (arising in part from a minor proportion of di-olefins in the initial olefin feedstock) some short chain monosulphonic acids arising as a result of scission of the olefin chain.

The immediate reaction product is believed to be a mixture of alk-2:3-ene-1-sulphonic acid and alkane- β -sultone. The latter, however, rapidly isomerises to the gamma and delta sultones which on alkaline hydrolysis yield alkane-3-hydroxy-1-sulphonic acid salts and alkane-4-hydroxy-1-sulphonic acid salts, respectively. The amount of residual sultone is such that less than about 2% of alkane-2-hydroxy-1-sulphonic acid salts are present in the mixture. The proportions of alkene sulphonate to total hydroxy alkane sulphonate are approximately as 2:1. The "disulphonate" factor may be as much as 1 proportion (i.e. about 25% of the total product), but by suitable choice of the quality of the olefin feedstock and of the reaction conditions (e.g. low concentration of SO_3 in the SO_3 /air stream) may be made substantially smaller. Products in which the "disulphonate" content is reduced to as low a value as practicable are preferred. By the term "alkene sulphonates" herein is intended the total reaction products as described above.

Thin layer chromatography may be used to separate the neutralised product into three zones corresponding, respectively, to the alkane hydroxy sulphonates, the alkene sulphonates and the "disulphonates," the relative amounts of which may then be determined.

Alkene sulphonates as defined above, prepared from about $C_{12-C_{24}}$ alpha-olefins (which may be obtained from a cracked-paraffin distillate, or synthesised from hydrocarbons containing fewer carbon atoms e.g. ethylene by the Ziegler or like catalyst, or by dehydration of primary alcohols derived by hydrogenation of esters of naturally occurring fatty acids such as vegetable or animal oils and fats, or in any other manner known to those skilled in the art), particularly such as contain only small proportions of the alkane-2-hydroxy-1-sulphonates, are particularly suitable for the preparation of toilet tablets as envisaged in the objects of this invention.

A particularly suitable alkene sulphonate is that having C_{14-20} or $C_{14-C_{16}}$ chain lengths.

The synthetic detergents with which the alkene sulphonates may be blended are for example, Igepon A, Igepon T, Igepon KT, Igepon 702K, salts of higher fatty acid sulphonates or their amides, alkylolamides or esters,

particularly mono-esters of polyalcohols such as glycol, glycerol and pentaerythritol, salts of sulpho-acetic esters of higher fatty alcohols, glycetyl mono-alkyl ether sulphates and sulphonates, glycetyl mono-acyl ester sulphates and sulphonates and fatty alcohol sulphates.

The degree of mildness exhibited by the compositions of the invention is greater than would be expected from a knowledge of the mildness qualities of the ingredients. Further, the bars have satisfactory plasticity and use properties. The undesirable mechanical properties of non-soap detergents which make them difficult to prepare as bars using the conventional toilet soap processes of milling, plodding and shaping by stamping are not shown by the compositions of the invention.

It has now been found surprisingly that the combination bars comprising essentially alkene sulphonates and fatty alcohol sulphates are not only readily processed to attractive bars free from cracking owing to reduced hardness, compared with tablets formed from alkyl sulphate as the sole active, but also exhibit marked synergistic lather volume when compared with tablets made from either component alone. The lather creaminess property is also greatly enhanced in tablets in which the alkene sulphonate component lies within the range 10% to 80% of the active.

Accordingly, this invention is particularly concerned with a toilet bar which consists essentially of synthetic detergents, wherein the synthetic detergents consist of an alkali metal or alkaline earth metal salt of an alkene sulphonate acid, in conjunction with an alkali metal alkyl sulphate.

The alkyl sulphates may be prepared, as is well known in the art, by the treatment of primary saturated alcohols with strong sulphonating agents. Means of sulphating unsaturated alcohols with retention of the double bond or bonds have also been long known in the art.

Particularly suitable alkyl sulphates are the C_{14-15} sulphates of synthetic primary alcohols. A commercial source of such synthetic alcohols is later described with reference to FIG. 1. Alternatively, alkyl sulphates may be used which are derived from a narrow distillation out of mainly C_{14-16} or C_{16-18} alcohols from natural sources or entirely n-primary alcohols of synthetic origin. A minor proportion of tallow alcohol sulphate, e.g. up to 25% by weight of composition or of the corresponding C_{16-20} synthetic alcohol sulphates may also be present. "Random" alkyl sulphates e.g. those commercially designated Teepol (RTM) are not envisaged as the major part of the alkyl sulphate component of the bar according to this invention. These improve the lather performance of the bar, but in higher amounts detract from the hardness. The alkyl 2-sulphate may be used in, say, up to 20% of the alkyl sulphate component.

The synergistic lather volume performance shown by the tablets according to the invention is graphically illustrated in the accompanying FIG. 1. These tablets contained as alkene sulphonate, a sodium alkene ($C_{15-C_{18}}$) sulphonate, derived from cracked wax synthetic olefins, and as alkyl sulphate, a $C_{14-C_{15}}$ synthetic sodium alcohol sulphate derived from Dobanol 45 (RTM)¹. (A mainly linear synthetic primary alcohol cut comprising mainly tetradecyl and pentadecyl alcohols of which about 30% are isomers of the n-alcohols and carry a short (e.g. methyl) alkyl group on the second carbon atom.) The lather volume test may be described as follows:

The hands of the operator are covered with thin surgical gloves. Water of the desired hardness and temperature is run to a depth of 3 inches into circular clear plastic bowls of 10 inches diameter at the base and 14 inches diameter at the top. This approximates to 1 Imperial gallon water. The gloved hands and the tablet are wetted by dipping and the tablet is twisted in the hands in a standardised manner 15 times. The lather on the

hands is worked by rubbing the hands back and forth and to and fro in a standardised manner 20 times each way (two alternating periods of ten rubs each) and the lather is transferred to a calibrated vessel. The total volume collected from three such operations is recorded as the lather volume.

Replicates by a trained operator may be made with good precision. Although replication between operators is poor, each operator ranks a series of tablets in the same order and records the same relative differences as do the other operators. The results quoted in this specification were obtained by a single trained operator. The graph of FIG. 1 was drawn smoothly amongst the points as detailed in the examples. It will be appreciated that the order of experimental error is in the region of ± 30 mls.

It will be understood by those skilled in the art that essentially similar results are obtained if the C_{15-18} sodium alkene sulphonate is replaced by a C_{14-18} or a C_{16-20} sodium alkene sulphonate made from alpha-olefins derived from Ziegler synthetic olefins or a C_{15-20} or C_{15-18} sulphonate from cracked wax olefins, and/or if the C_{14-15} synthetic sodium alcohol sulphate is replaced by a C_{14-16} distillation cut of fatty alcohols derived from synthetic n-alcohols, e.g. those manufactured from alpha-olefins, especially Ziegler olefins, by the oxo process, natural fats such as coconut oil, or palm kernel oil. A minor proportion of C_{15-24} sulphonates (either Ziegler or cracked paraffin derived) may also be present.

The synergistic lather volume effect is demonstrated by compositions in which the alkene sulphonate is present in amount 95% to 5% of the total active and the alkyl sulphate in amount 5% to 95% of the total active, preferably in respective amounts of 70:30 to 30:70. The total active may comprise at least 75% by weight of the total composition.

The lather creaminess is very marked with the compositions of the invention. The term "lather creaminess" is well understood by those skilled in the art but is extremely difficult to define. It expresses an intuitive subjective impression compounded of the qualitative appraisal of the mode (most common size) of bubble sizes, the "whiteness" of the lather, and, particularly, its "resilience" or "thickness" as appreciated by the tactile senses. The "creaminess" was judged on a scale represented by the words: very poor, poor, poor-fair, fair, fair-good, good, very good, excellent, associated with the numerical scale:

0, 1, 2, 3, 4, 5, 6, 7

The "creaminess value" of the lather given by the tablets whose lather volumes are given in FIG. 1, are plotted in the accompanying FIG. 2. It is clear that the creaminess values of the bars of the invention rise substantially above those expected from a linear interpolation between the values at the extremes of 100% alkene sulphonate and 100% alkyl sulphate.

In the tablets according to the invention, the amount of alkene sulphonate used may be 20-60% and the total of alkene sulphonate and the other selected non-soap detergent is preferably in the range of 50-90% by weight of the composition.

The tablets according to this invention can be improved in respect of their "slip" property. It is known that many water-soluble polymeric substances of extremely high molecular weight, when added in very small amounts (usually less than 0.1%) confer a desirable "slip" in detergent toilet tablets, but that in larger amounts (e.g. more than 0.3%) this slipperiness increased to an intolerable degree of sliminess. Such substances include partially hydrolysed polyacrylamides, super-polyglycols (Polyox (RTM)), and sodium polyacrylates. These substances are highly viscous, and also highly viscoelastic in dilute, e.g. 0.5% w./w., solution. The extreme viscoelasticity confers upon the tablet the intolerable sliminess above-mentioned. If the concentration is reduced so as to gain the "slip" effect

¹ Known as "Neodol 45" in the United States.

without sliminess, the solutions are no longer able to confer high viscosity upon the system as a whole.

The invention will now be described by way of examples.

ides gums or mucilages or synthetic polymeric substances for imparting "slip" when desired, or binders such as starch, starch lower alkyl ethers, starch lower alkoxyethers, starch lower alkyl carboxy ethers, starch lower

Adjuvants (pigment, perfume etc.)	1.5	1.5	1.5
Water	10	10	10

(Note that olefins catalytically formed from ethylene and also those made by dehydration of fatty alcohols from natural sources, are mixtures of even-numbered carbon atom chains, whereas those derived from cracked paraffins are mixtures of both odd and even-numbered carbon atom chains. The "cuts" quoted in the above examples are to be taken to include both even-numbered chains only and even-plus-odd numbered chains, averaging about the same mean molecular weight and spanning approximately the same range in numbers of C atoms in the chains.)

The tablets used for this work were readily manufactured on laboratory scale equipment designed to reproduce as nearly as possible the conditions of full scale manufacture. The formulations were milled three times on a three roller mill followed by crimping and plodding through a die giving a bar of cross section 1 3/4" x 3/4" which was stamped to tablets measuring 1 3/4" x 5/8" x 2 5/8". The bars so produced were satisfactory in appearance and in wear and storage properties and were substantially non-irritant.

Whilst the invention has been specifically described in the examples, mainly with reference to sodium salts, other alkali metal or alkaline earth metal salts of the suphonates or alkali metal sulphates may be used similarly. It is also possible to employ mixed cations, i.e. to use, as alkene sulphonate component, a mixture selected from sodium, potassium and magnesium alkene sulphonates. It is also possible to employ alkene sulphonates of differing carbon chain length in conjunction with each other. The required blend of alkene sulphonates may be obtained by sulphonation of a blend of olefins of the desired distribution of carbon chain lengths, or by admixture of sulphonation products of olefins of single chain lengths.

Minor amounts of other ingredients which may be added, known to those skilled in the art, include the following: lather modifiers such as higher aliphatic straight or branched paraffins, fatty acids, fatty alcohols, fatty amides, fatty alkylolamides, fatty ureides, or fatty guan-

20 alkyl sulphonate ethers, cellulose lower alkyl ethers, cellulose lower alkoxy ethers, cellulose lower alkyl carboxy ethers, cellulose lower alkyl sulphonate ether, locust bean gum, guar gum, slippery elm mucilage, chondroitin sulphate, proteins, polypeptides, polyacrylamides, very high molecular weight water-soluble polymers and copolymers of vinyl alcohol, maleic acid, acrylic acid, itaconic acid, pyrrolidone, or allyl alcohol, polyoxyalkylene oxides particularly polyethylene oxides e.g. Carbowaxes (RTM), Polyoxes (RTM), a proportion of the polymerised monomer units optionally carrying a carboxy, sulphate, sulphonate, phosphate or phosphonate ionising group; colouring agents, pigments, bactericides, fungicides, preservatives, perfumes, sequestering agents, glucose, glycerine and other polyols, or other low-molecular water-soluble hydrogen bond forming substances such as urea; electrolytes such as sodium chloride, sodium sulphate, sodium lactate, and sodium phosphate, pyrophosphate or polyphosphate.

What is claimed is:

- 40 1. A synthetic detergent toilet bar which consists essentially of (a) from about 30% to about 70% by weight of a mixture of an alkali metal or alkaline earth metal salt of an alkene sulphonic acid having 11-24 carbon atoms and a hydroxy-alkane sulphonate, said hydroxy-alkane sulphonate being a mixture of alkane-3-hydroxy-1-sulphonate, alkane-4-hydroxy-1-sulphonate and alkane-2-hydroxy-1-sulphonate, wherein no more than 2% by weight of said mixture of hydroxy-alkane sulphonate is the alkane-2-hydroxy-1-sulphonate and the weight ratio of the salt to the hydroxy-alkane sulphonate mixture is about 2 to 1, together with (b) from about 70% to about 30% by weight of a primary alkyl sulphate wherein the alkyl group has from 14-20 carbon atoms.
- 45 2. A bar according to claim 1 wherein said sulphonate has 14-20 carbon atoms.
- 50 3. A bar according to claim 1 wherein said sulphate is a mixture of synthetic primary alcohol sulphates of 14 and 15 carbon chain lengths, and which have about 30% branching at the 2-position.
- 55 4. A bar according to claim 1 wherein said salt is a mixture of salts of different cations being selected from the group of sodium, potassium, magnesium and calcium.

UNITED STATES PATENT OFFICE
CERTIFICATE OF CORRECTION

Patent No. 3,523,089

Dated August 4, 1970

Inventor(s) Horace Edward Garrett

It is certified that error appears in the above-identified patent and that said Letters Patent are hereby corrected as shown below:

Column 1, line 18, the word "alkene" should read --alkane--.

Column 2, lines 8 through 16 delete "and provided with..... disulphonic acids" inclusive and insert in place thereof --and provided with a means for removing the heat of reaction. A reaction product is obtained which, on acidic hydrolysis followed by neutralisation, or by alkaline hydrolysis yields salts of sulphonic acids. These sulphonic acids are complex mixtures of alkane hydroxy sulphonic acids and alkene acids, with a proportion of sulphonic acids of low equivalent weight which are conveniently termed "di-sulphonic acids", without implying that they are wholly true disulphonic acids.--

Column 4, line 25, the word "alpho" should read --alpha--.

Columns 5 and 6, description under "Example No.", line 3, "C₁₄-15" should read --C₁₄-18--, and the word "suophonate" should read --sulphonate--.

line 5, "C₁₈-30" should read --C₁₈-20--.

line 12, "28° Heater" should read
--28°H water--.

Column 5, line 22, the figure "19" should read --18--.

line 34, "C₁₆-30" should read --C₁₆-20--.

Column 6, line 30, the word "corboxy" should read --carboxy--.
